UNITED STATES PATENT OFFICE.

JONATHAN MCKELVEY, OF LOUISVILLE, KENTUCKY, ASSIGNOR OF ONE-FIFTH TO WILLIAM H. STIGLITZ, OF LOUISVILLE, KENTUCKY.

AMALGAMATOR.

SPECIFICATION forming part of Letters Patent No. 699,550, dated May 6, 1902.

Application filed September 23, 1901. Serial No. 76,139. (No model.)

To all whom it may concern:

Be it known that I, JONATHAN MCKELVEY, a citizen of the United States, residing at No. 2415 Portland avenue, Louisville, in the county of Jefferson and State of Kentucky, have invented certain new and useful Improvements in Amalgamators; and I do declare the following to be a full, clear, and exact description of the invention, such as will enable others skilled in the art to which it appertains to make and use the same, reference being had to the accompanying drawings, and to the letters of reference marked thereon, which form a part of this specification.

In the drawings, Figure 1 is a transverse sectional view of my amalgamator through the line $x-x$ of Fig. 2. Fig. 2 is a vertical transverse sectional view of the same on the line $x'-x'$ of Fig. 1. Fig. 3 is a rear elevation of the amalgamator. Fig. 4 is a sectional detail view of the column C, showing the inclination of the slots therein. Fig. 5 is a detail sectional view of a suitable construction of valve which may be employed to permit withdrawal of amalgam.

My machine, constructed, preferably, of iron castings, consists of a case P, oblong, with rounded ends in horizontal cross-section, within which is arranged a central tubular feed or sluice column C, surmounted by a detachable funnel I, extending above the top Q of the case P. The lower end of this sluice-column, which in front and rear rests on the sides of P, opens into a mercury-holding basin formed by the bottom of the case P below the line W, which marks the top surface of a body of mercury. The column C is surrounded by a chamber H, formed by the three walls Y Y and Y' and the front wall of P, as shown in Fig. 1. The rear cross-wall Y' is placed a short distance inside the rear wall of P, forming a small chamber H', as shown. The walls Y incline inwardly till their bottoms impinge on the outer surface of C. On opposite sides of the chamber H in chambers G G are arranged overflow-pipes A and B, whose top diameters are twice as great as that of C and which taper downward to smaller dimensions till their lower ends meet the center column and the sides of and ends of P. In the in-

ner wall of this chamber H' is an aperture S', communicating with the chamber H, and in its side walls are apertures Z Z, communicating with chambers G, formed between the outlet-pipes A and B and the walls of the case P. Through the walls of the sluice-column C are apertures E, constructed so as to be at an angle of forty-five degrees to the vertical axis of the column and inclined in their passage through the walls of the column at a similar angle to its horizontal diameter. Near the bottom of the column are apertures E', constructed at downward angles to the vertical axis of about twenty degrees and angles of about forty-five degrees to the horizontal diameter of the column. At intervals in the walls of the outlet-pipes A and B are apertures D D. Said apertures are preferably arranged at angles of about forty-five degrees to the horizontal diameter of the pipe and cause the water to enter the overflow-pipes in a way which causes the material therein to be given a whirling motion.

R is an aperture in the rear wall of the case P (shown in Fig. 3 and in dotted lines in Fig. 2) for the admission of water under pressure through a pipe.

S is the end of a valve-handle which controls the aperture S' in the inner wall Y' of the chamber H'. S' is shown in Fig. 3 and in dotted lines in Fig. 2.

F is a flange around the upper edge of the wall P, to which the top Q is fastened by nut-bolts.

The operation of my amalgamator may be described as follows: The bottom of the case P is filled with mercury up to the line W. The gold-bearing sand or other disintegrated gold-bearing material is poured into the funnel I and passes down through the tubular column C into the mercury-well. At the same time water under pressure is admitted through the aperture R into the chamber H', whence it passes through the opening S' into the chamber H and thence through the apertures E and E' into the sluice-column C and through the apertures Z Z into the chambers G and thence through the apertures D D into the overflow-pipes A and B. The water passing into the descending gold-bearing material through the apertures E is given a whirling motion.

ing downward motion, which, in order to prevent too much disturbance of the mercury and liability to its being carried off in the tailings, is broken by the water coming through 5 the apertures E' near the bottom at an angle nearer the horizontal. The gold-bearing material after passing through the mercury and depositing its gold is carried up through the overflow-pipes A and B, from which it flows 10 through exit-openings Q', which are preferably formed in the cover Q and register with the open tops of the overflow-pipes A and B. In said overflow-pipes the gold-bearing material is still further broken up by the whirling 15 motion given to it in there by the water coming through the apertures D D, and thus encouraged to drop any particles of gold that have been protected from contact with the mercury. When it is desired to clean the 20 outlet-pipes A and B, the aperture S' is closed by the valve S and the water passes through the apertures Z Z into the chambers G and thence through the apertures D D into the outlet-pipes A and B.

25 The means for withdrawing the amalgam is shown in Figs. 2, 3, and 5 and embraces a hollow screw-valve K at the bottom of the case P. V represents one side of a stand which supports said case, and T T designate 30 legs of said stand.

Having thus described my invention, what I claim as new, and desire to secure by Letters Patent, is—

1. In an amalgamator, the combination with 35 a case having a mercury-holding basin and provided with chambers and having means for admitting water under pressure to said chambers, of a sluice-tube in one of said chambers and an outlet-pipe in another of 40 said chambers, said tube and pipe each having communication with said basin and each having series of openings for the admission thereto of water from their respective chambers, substantially as described.
- 45 2. An amalgamator embracing a casing having a mercury-holding basin and a sluice-tube in communication with said basin, and means for admitting water to said sluice-tube embracing series of downwardly-inclined openings therein of which the lower ones are at an angle to the others and a water-pressure chamber surrounding the sluice-tube, for the purpose set forth, said amalgamator also having means through which water is supplied there- 50 to, means for withdrawing amalgam and conducting means for the tailings.
- 45 3. An amalgamator having its sluice-tube provided with a series of downwardly-inclined openings of which the lower ones are at an angle to the others, said amalgamator also having a basin for mercury in communication with 55

said sluice-tube and a conducting means for tailings in communication with said basin, combined with a water-supplying means.

4. In an amalgamator, the combination with 65 a case having a mercury-holding basin, provided with means for withdrawing amalgam therefrom, said casing also having outer chambers, an intermediate chamber and a separate chamber having openings leading to said outer 70 and intermediate chambers and provided with means for the admission of water under pressure to said separate chamber, in combination with overflow-pipes in said outer chambers, having apertured walls for the admission 75 of water thereto, and a sluice-tube in said intermediate chamber, having openings for the admission of water from said intermediate chamber, said pipes and tubes having communication with said basin, substantially as 80 described and for the purposes specified.

5. In an amalgamator, the combination with 85 a case having a mercury-holding basin, provided with means for withdrawing amalgam therefrom, said casing also having outer chambers, an intermediate chamber and a separate chamber having openings leading to said outer and intermediate chambers, and means through which water under pressure is admitted to said separate chamber, of a sluice-tube in said intermediate chamber, having a series of downwardly-inclined apertures for the admission thereto of the water from said intermediate chamber, the apertures near the lower end of said tube extending through the 95 wall of the same at an angle nearer the horizontal than those above, and overflow-pipes in said outer chambers, having non-radial apertures in their walls for the admission of water from their respective chambers, said 100 tube and pipes having communication with said basin, substantially as described and for the purposes specified.

6. An amalgamator having its sluice-tube 105 provided with a series of downwardly-inclined openings of which the lower ones are at an angle to the others, said amalgamator also having a basin for mercury in communication with said sluice-tube and an overflow-pipe in communication with basin, said overflow-pipe being formed with apertures so arranged as to cause the water entering the pipe through the same to give a whirling motion to the material in said pipe, and means through which water is supplied to said sluice-tube and overflow- 110 pipe.

In testimony whereof I affix my signature in presence of two witnesses.

JONATHAN MCKELVEY.
